UNITED STATES PATENT OFFICE.

SHANNON L. VANALST, OF DOUGHTY, BRITISH COLUMBIA, CANADA.

PENCIL-SHARPENER.

1,326,429.

Specification of Letters Patent. Patented Dec. 30, 1919.

Application filed July 30, 1917. Serial No. 133,583.

To all whom it may concern:

Be it known that I, SHANNON L. VANALST, a subject of the King of Great Britain, residing at Doughty, in the Province of 5 British Columbia and Dominion of Canada, have invented certain new and useful Improvements in Pencil-Sharpener, of which the following is a specification.

This invention relates to pencil sharpeners 10 of that type including a hollow conical rotary cutter into which the pencil is inserted to be sharpened by the blade of the cutter.

The object of the invention is to provide a simply constructed and efficient device of 15 this character which may be mounted upon any suitable support and readily assembled or disassembled when desired.

Another object is to improve and simplify pencil sharpeners of this type so as to be reliable and efficient in use and in which the point of the pencil is protected while being sharpened and all possibility of its becoming broken while in the sharpener is prevented.

With the foregoing and other objects in 25 view, which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

In the accompanying drawings:—

35 Figure 1 represents a front elevation of this improved sharpener shown applied,

Fig. 2 is a transverse section taken on the line 2—2 of Fig. 1,

Fig. 3 is a similar view taken on the line 40 3—3 of Fig. 1, and

Fig. 4 is a central longitudinal section taken on the line 4—4 of Fig. 2.

In the embodiment illustrated, the pencil sharpener constituting this invention comprises 45 a pair of supporting brackets 1 and 2 which are here shown in the form of substantially triangular plates having laterally extending apertured ears 3 for the passage of the fastening elements which are designed 50 to connect the brackets to the wall of a room or to a desk or to any other suitable support. These brackets are spaced apart a suitable distance to receive between them and

the support a shaving receiving receptacle 4 which is here shown semi-cylindrical in cross 55 section, being provided at its opposite ends with upstanding lugs 5 having downwardly opening slots 6 therein which are adapted to hook over studs 7 projecting laterally from the inner faces of the brackets 1 and 2 as is 60 shown clearly in Figs. 1, 3 and 4.

The upper edges of the brackets 1 and 2 are provided with bearings which are here shown in the form of recesses 8 and 9 disposed in alinement with each other when the 65 brackets are mounted in operative position as shown in the drawings, the recess 8 in bracket 1 being larger than the recess 9 in bracket 2 for a purpose presently to be described. 70

The sharpener proper comprises a one-piece cutter in the form of a hollow sheet metal conical body 10 which is provided in one wall thereof with a longitudinally extending slot 11 in which is mounted a cutting blade 12 which extends inwardly into the member 10 in the path of the pencil to be sharpened. This conical body 10 is provided at its larger end with an annular closure 75 provided with a tubular extension 13 having 80 a flared mouth 14 and which is designed to form a guide for the entrance of a pencil to be sharpened.

The tapered smaller end of the conical body 10 is also provided with a tubular extension 15 which communicates with the interior of the body and one end of which is designed to form a protector for the point P of the pencil P' being sharpened as is shown clearly in Fig. 4, the extension being 90 in alinement with said point so that no obstruction will be offered such as would break the point. The outer end of this extension is designed to receive shaft 16 which rests in the smaller recess 9 of bracket 2 while the 95 tube 13 at the opposite end of the sharpener rests in the larger recess 8 of bracket 1, these recesses forming bearings for the sharpener which is designed to be revolved therein by a crank handle 17 which is detachably engaged with the projecting angular end 18 of the shaft 16 as is shown clearly in Figs. 1 and 4.

In the use of this sharpener, the brackets 1 and 2 having been fastened to the desired 105 support, the shaving receiving receptacle

4 is engaged with the studs 7 of said brackets and the sharpener proper is mounted in the recesses 8 and 9. The handle 17 is then engaged with shaft end 18 and 5 the device is ready for use. The pencil P is then inserted through the flared mouth 14 of the tubular extension 13 and projected inwardly into the body 10 as far as it will go, and when in this position the pencil is 10 held in one hand of the operator and the crank handle 17 is engaged by his other hand and thereby rotated relatively to the pencil, causing the cutting blade 12 to sharpen the point thereof. After the point has been 15 sharpened it may be withdrawn from the sharpener and the device is ready for the next use.

From the foregoing description, taken in connection with the accompanying drawings, the advantages of the construction and of the method of operation will be readily apparent to those skilled in the art to which the invention appertains and while I have described the principle of operation of the 20 invention together with the device which I now consider to be the best embodiment thereof, I desire to have it understood that the device shown is merely illustrative and 25

that such changes may be made as are within the scope of the claimed invention. 30

I claim:—

In a pencil sharpener, the combination of a pair of plates having apertured attaching ears, and provided in their upper edges with semi-circular recesses to form bearings, 35 one being larger than the other, a one-piece sheet metal pencil holder and cutter comprising a hollow cone-shaped head carrying a longitudinally extending blade in one side wall, said head merging at its smaller end 40 into a tubular point and handle receiving extension projecting longitudinally therefrom and adapted to rest in the smaller bearing, the larger end of said head having an annular closure with a tubular pencil support extending from the center thereof and flared at its outer end, a handle fitted in the outer end of said first-mentioned tubular extension, and a receptacle removably supported by said plates below said sharpener. 45 50

In testimony whereof I affix my signature in presence of two witnesses.

SHANNON L. VANALST.
